UNITED STATES PATENT OFFICE.

GUSTAV STROM, OF PONTIAC, MICHIGAN, ASSIGNOR OF FORTY-NINE ONE-HUNDREDTHIRTY-THREE TO PETER D. JOHNSTON, OF PONTIAC, MICHIGAN.

APPARATUS FOR BUILDING CONCRETE STRUCTURES.

Application filed July 2, 1921. Serial No. 482,040.

To all whom it may concern:

Be it known that I, GUSTAV STROM, a citizen of the United States of America, residing at Pontiac, in the county of Oakland and State of Michigan, have invented certain new and useful Improvements in Apparatus for Building Concrete Structures, of which the following is a specification, reference being had therein to the accompanying drawings.

The invention relates to the apparatus for forming building walls of cement or concrete and it is the object of the invention to facilitate the manufacture of slab units which may be used in the erection of such walls. It is a further object to provide for various forms of finish, such as imitation stone, brick, etc. and to this end the invention consists in the apparatus as hereinafter set forth.

In the drawings:

Figure 1 is a plan view illustrating the method of setting up the molds and for disassembling the same after the setting of the molded slabs;

Figure 2 is a perspective view of the mold sections disassembled;

Figure 3 is a cross-section showing a stack of filled molds;

Figure 4 is a horizontal section showing the manner of engaging and disengaging the wall sections;

Figure 5 is a vertical section through a mold provided with an attachment for forming an imitation brick face;

Figure 6 is a perspective view of the attachment used in Figure 5;

Figure 7 is a perspective view of one of the finished slabs;

Figure 8 is an enlarged detail view showing the manner of disengaging a wall section.

In the erection of building walls formed of concrete blocks it is usual to lay the blocks with an ordinary mortar binder. With my improvement the blocks are designed to be attached by fluid cement and are therefore of a form for receiving the cement and for forming thereby the necessary keys. To manufacture such blocks cheaply and expeditiously, I employ forms which may be quickly set up and knocked down and by which a series of slabs or blocks may be simultaneously molded.

In detail, A is a series of molds, each one

of which is composed of members B and C detachably engaging each other to form a rectangle. These members are preferably formed of pressed sheet metal and, as indicated in Figure 2, each is formed with a rib or bead D arranged centrally and extending longitudinally thereof. The members B are further provided near their opposite ends with slots E and the members C are formed at one end with projecting offset ears F having a slot G therein, while at the opposite end there is a hook H for engaging the slots G of an adjacent member C. The arrangement is such that in assembling the mold, the ears F are first inserted through the slots E and the hooks H are then inserted through the slots G, which arranges the second member C in alignment with the first and clamps the member B therebetween. In this manner a series of molds may be laid, the members B forming division strips between adjacent blocks and the beads D thereof forming in one block a groove and in the adjacent block a tongue. The tongue I is smaller than the groove J to an extent equal to the thickness of the member B and this provides a space for filling with a binding cement when the blocks or slabs are laid in the wall. The beads D upon the section C extend inward so as to form grooves K in the opposite ends of the blocks. These grooves, when filled with plastic cement, in the laying of the wall will form keys binding adjacent blocks to each other.

To economize in ground space the series of molds are preferably arranged in stacks having a plurality of superposed molds. The method of procedure is, first, to assemble the series of molds, constituting the base of the stack, resting the same upon a suitable base-board L. These molds are then filled with plastic cement and are struck off, after which a pair of wooden strips M, M' are placed on opposite sides of the series and another board L' is supported thereon. Upon this a second series of molds is assembled, being filled and struck off in the same manner and this operation is continued until the whole stack is formed. After the setting of the cement, the molds are successively disassembled by swinging the end sections C about the slotted ears F and hooks H as a pivot until said hooks are disengaged from the slots, then withdrawing the section B from engagement with the ears of the next

mold, removing the section C therefrom by swinging outward in the same manner as before described, and so continuing until all of the sections are disassembled. Each block, when free, is removed from the stack and placed, preferably in vertical position on a bed of sand, where it is permitted to remain until the cement has sufficiently hardened for transportation. The layers of the stack are successively removed in this manner and when all the blocks have been detached, the molds may be again refilled.

It is frequently desired to build a cement wall in imitation of a brick or other finish. To accomplish this, I have provided an attachment, shown in Figures 5 and 6, in which N is a frame or grid marked off to conform to the standard arrangement of bricks in a wall, the divisions of the frame being of a thickness equal to the usual thickness of the mortar. The depth of the frame is comparatively slight, as, for instance, one-fourth of an inch. In use, after the main mold has been filled and struck off to form the body of the slab, the frame N is placed thereon and the openings filled with a cement suitably colored in imitation of brick. After striking off the cement, the frame is lifted and will leave the projecting brick, while the grooves between the same will have the appearance of mortar.

In laying a wall the slabs or blocks formed as described are assembled end to end and the grooves K are filled with liquid cement. This, when hardened, will form a key firmly binding the blocks to each other. The superposed blocks are connected by filling the groove with cement and then inserting the tongue of the adjacent block which, as before described, is slightly smaller and will leave room for the cement. In this manner the wall may be built and if desired, may be made hollow by use of a parallel inner wall and suitable spacer blocks.

One of the principal advantages of my improvement is the low cost of the molding frames and the ease with which such frames can be assembled and disassembled. Also, my method of forming the face by the shallow superposed frame is one which lends itself to great and cheap production.

What I claim as my invention is:

1. A mold for cement blocks or slabs comprising a plurality of pairs of parallelly arranged side members, each having a projecting apertured ear at one end thereof, and a hook at the opposite end, cross members apertured to engage said ears and secured by the engagement of hooks of an adjacent pair therewith.

2. A mold for cement blocks or slabs, com-

prising side and end members formed of pressed sheet metal, having a longitudinally extending central bead for forming a groove or tongue when oppositely arranged, said side members being provided with projecting apertured ears at one end and hooks at the opposite end for engaging the apertures of ears on adjacent side members, and said end members being apertured for engagement with said ears and held in position by the hooks.

3. A mold for cement blocks or slabs comprising a plurality of pairs of parallelly arranged side members, each member having an apertured ear at one end thereof and a hook at the opposite end for engaging an aperture of the corresponding ear, whereby said pairs of side members may be arranged end to end in a series of any desired length, cross members apertured for engagement with said ears and locked in position by the hooks engaging said ears, the hooks on the members on opposite sides of the mold being oppositely turned to permit of disengagement from the molded block by a pivotal or swinging movement.

4. A mold for cement blocks or slabs comprising a body portion formed of intersecting side and end members, and a facing member in the form of a grid superposed on said body portion between said intersecting side and end members.

5. A mold for cement blocks or slabs comprising a plurality of pairs of metallic side members, each having a projecting apertured ear at one end thereof, a hook at the opposite end, and metallic cross members apertured to engage said ears and secured by the engagement of hooks of an adjacent pair therewith.

6. A mold for cement blocks or slabs, comprising a plurality of pairs of side members, each having an integral projecting apertured ear at one end thereof, an integral hook at the opposite end, and cross members apertured to engage said ears and secured by the engagement of hooks of an adjacent pair therewith.

7. In a mold of the class described, a plurality of spaced members having openings therein at the ends thereof, spaced members extending through said openings, the last-mentioned members having apertures therein at one end and provided with hooks at the opposite end, said hooks being engageable with said apertures for holding the last-mentioned members in the openings in the first-mentioned members.

In testimony whereof I affix my signature.

GUSTAV STROM.
